UNITED STATES PATENT OFFICE.

ADAM K. BOWMAN, OF GREENSBURG, PENNSYLVANIA.

GARMENT-HANGER.

SPECIFICATION forming part of Letters Patent No. 625,137, dated May 16, 1899.

Application filed September 14, 1898. Serial No. 690,942. (No model.)

To all whom it may concern:

Be it known that I, ADAM K. BOWMAN, of Greensburg, in the county of Westmoreland and State of Pennsylvania, have invented a new and Improved Garment-Hanger, of which the following is a full, clear, and exact description.

The object of my invention is to provide a device that may be adjusted to suit the garments of males or of females, but which is particularly intended as a skirt-supporter.

A further object of the invention is to so construct such a hanger that it will be simple, durable, economic, and self-adjusting and which will support the skirt below the waistband without interfering in the least with the proper contour of the skirt at the hips.

A further object of the invention is to provide a garment-hanger that will take up but little space and that may be used in connection with a skirt of any waist measurement and upon which the skirt may be expeditiously and conveniently placed and the device as readily removed from the skirt whether the skirt be in a vertical or in a horizontal position, the removal being effected by the aid of one hand only.

A further object of the invention is to so construct the hanger that it will not leave the skirt in any position in which the skirt may be placed in handling and wherein even should the waistband become unbuttoned the skirt will not leave the hanger.

A further object is to so construct the hanger that there are no sharp or rough corners and so that when the hanger is applied to a garment but a slight portion of the hanger will be visible, thus rendering the device effective for display purposes.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in both figures.

Figure 1 is a side elevation of the device, illustrating the application of a skirt thereto; and Fig. 2 is a side elevation of the device, the skirt having been removed.

The device is preferably made of a single

piece of spring-wire, and the said wire is bent upon itself to form two base-bars 10 and 11, which extend in opposite directions and are 55 at an angle to each other, and between these bars 10 and 11 a coil 12 is formed, the coil being at the lower central portion of the device. The wire is carried from the upper ends of the base-bars 10 and 11 upwardly and inwardly to form supporting bars or sections 13, and where the supporting bars or sections 13 connect with the base or bottom bars 10 and 11 the corner is rounded off, and at the upper end portions of the supporting bars or 60 sections 13 the wire is bent upon itself to form eyes or knobs 14, as is particularly shown in Fig. 2. From each eye 14 the wire is carried downwardly to the central portion of the coil 12, forming two converging upper 65 bars 15 and 16. The wire forming the upper bar 15 is bent upon itself to form a single coil or ring 17 over the central portion of the main coil 12, and the wire after the said ring or single coil 17 is formed is looped over one of the 70 members of the main coil 12, as shown at 18 in Fig. 2, and is then carried upwardly to form a strand 19 of a shank A, located centrally and vertically between the upper members 15 and 16. The wire of the upper member 75 16 is likewise bent upon itself over the main coil 12 to form a single coil or a ring 20, and the wire after the ring 20 is formed is looped over the main coil 12 at the opposite side of the center of the loop 18, the loop of 80 the ring or single coil 20 being designated as 21, and the wire is thence carried from the loop 21 in a single strand 22, and the two strands 19 and 22 are twisted together to render the shank A exceedingly strong, and the 85 wire of the shank is formed into a hook 23 at its upper end. One end of the wire after being returned downward in the formation of the hook 23 is held in place by the other end of the wire, which is twisted or coiled around it, 90 as shown at 24 in Fig. 2.

It will be evident from the construction shown and described that the supporting bars or sections 13 and the bars 15 and 16 constitute "wings" and are so termed in the appended claims.

In operation the skirt is placed on the hanger so that the waistband will be immediately below the knobs or eyes 14, and the

hip portion of the skirt will rest upon the supporting-sections 13. If the waistband is of small measurement, the wings at each side of the shank A will be drawn together, and if the measurement of the waistband is large the weight of the skirt on the supporting-sections 13 will cause the said sections to drop until the proper tension is obtained between the aforesaid wings of the device and the skirt.

10 It is evident that even should the waistband become unbuttoned the skirt could not drop from the device, since the weight of the skirt would carry the wings downward until they had spread sufficiently apart to hold the skirt as firmly as if the waistband were buttoned.

In the event the skirt is very heavy at the back or is provided with a train a portion of the twist or coil 24 may be carried rearward 20 and returned to provide a supporting-arm 25, over which arm the upper rear portion of the skirt may be passed.

Having thus described my invention, I claim as new and desire to secure by Letters 25 Patent—

1. A garment-hanger, comprising skeleton wings extended in opposite directions and each at an upward and outward inclination, each wing being provided with an inclined 30 end supporting-section, a coil connecting the lower members of the wings and a shank ex-

tended upward from the junction of the two wings, as and for the purpose specified.

2. A garment-hanger, constructed of spring-wire, comprising skeleton wings at an angle 35 to one another, said wings extending in opposite directions and in an upward and outward direction, each wing being provided with an inclined end supporting-section, a coil connecting the lower members of the 40 wings, and single coils connecting the shank with the upper member of the wings, as and for the purpose specified.

3. A garment-hanger, comprising two wings at an angle to one another, said wings being 45 oppositely disposed, and having an upward and outward inclination, the lower members of the wings being connected by a coil, each wing having an inclined end supporting-section and an offset at the upper edge of its 50 supporting-section, a shank provided with means of suspension, and single coils or rings forming an integral portion of the shank, the said single coils or rings being looped around the connecting-coil for the wings at each side 55 of the center of said connecting-coil, for the purpose specified.

ADAM K. BOWMAN.
